CLAIM

The ornamental design for a vehicle tyre, as shown and described.

DESCRIPTION

1. Vehicle tyre
 1.1 : Back
 1.2 : Front
 1.3 : Bottom
 1.4 : Perspective
 1.5 : Top
 1.6 : Left
 1.7 : Enlarged top view wherein the area of enlargement is identified by the broken-line region **1.7** within Reproduction **1.5**
 1.8 : Right
 1.9 : Transverse section view taken along line **1.9-1.9** in Reproduction **1.8**
 1.10 : Enlarged transverse section view, wherein the area of enlargement is shown in the broken-line region **1.10** within Reproduction **1.9**
 1.11 : Perspective view of the enlarged section view shown in Reproduction **1.10**
 The present design relates to a tyre for vehicle; the broken lines showing the remainder of the tyre are for environmental purposes only and form no part of the claimed design.
